UNITED STATES PATENT OFFICE.

CHARLES N. BRETT, OF VASSAR, MICHIGAN

HEATING-FURNACE.

No. 815,140.

Specification of Letters Patent.

Patented March 13, 1906.

Application filed May 20, 1905. Serial No. 261,402.

To all whom it may concern:

Be it known that I, CHARLES N. BRETT, a citizen of the United States of America, and a resident of Vassar, county of Tuscola, State 5 of Michigan, have invented certain new and useful Improvements in Heating-Furnaces, of which the following is a full and clear specification, reference being had to the accompanying drawings, in which—

10 Figure 1 is a perspective view with the outer casing broken away to better show the flue arrangement. Fig. 2 is a vertical longitudinal section of the furnace. Fig. 3 is a horizontal section on the line 3 3 of Fig. 2. Fig. 4 is a 15 vertical section on the line 4 4 of Fig. 2. Fig. 5 is a vertical section on the line 5 5 of Fig. 2; and Fig. 6 is a detail perspective view of the front end of the fire-box, the front wall of the casing being removed for purposes of 20 better illustration.

The object of this invention is to provide a heating-furnace which shall be simply constructed and give the maximum of heating efficiency with a given amount of fuel, as 25 more fully hereinafter set forth.

To the accomplishment of this object and such others as may hereinafter appear the invention consists of the parts and combination of parts hereinafter fully described, and 30 particularly pointed out in the appended claims, reference being had to the accompanying drawings, forming a part of this specification, in which the same reference characters designate like parts throughout the several 35 views.

Referring to the drawings by letters, A designates the inclosing casing, to which hot-air pipes (not shown) may be attached in the usual way and which is of the usual construction, except that its front wall is constructed of a series of plates riveted or bolted together, this sectional form of the front wall being desirable on account of convenience in manufacture, repair, and transportation.

45 The letter B designates the casing of the furnace proper, which is elliptical in shape in cross-section and is constructed of sheet-steel bent into shape. The front and rear end 50 walls C of the furnace each consists of a cast-iron plate having a flange b^2 cast on its inner face, which fits within the elliptical casing. Each end wall is also provided with lateral ears c, through which the securing-bolts b 55 pass, these bolts being flattened and riveted to the exterior of the casing or the body B

and having their threaded ends passing through said ears and provided with nuts, whereby the end walls may be fastened securely, but removably, to the body-shell. 60

The smoke-flue J is connected to a flanged opening in the rear wall C, and a damper j is mounted in this flue and is controllable by a rod j', extending forward through the front wall of the casing. 65

Extending out laterally from each side of the combustion-chamber, at the rear end thereof, is a flue e, which is connected to the shell by a suitable flange riveted to the exterior thereof. Each of these flues e extends 70 forward to an opening in the front wall of the casing, this opening being closed by a removable clean-out cap f. Connected to each flue e near its forward end is a downward-extending flue g, whose lower end communicates 75 with a flue h, which lies parallel with said flue e and likewise has its forward end accessible through an opening in the front wall of the casing, this opening also being closed by a removable cap i. 80

The flues h are supported on suitable brackets fastened to the furnace-shell and extend around back of the same, where they are connected together and to an upright flue o', which is connected to the smoke-flue J at 85 a point beyond the damper.

Cast integral with the front wall C are two casings K and P, which are respectively provided at their forward ends with slotted lateral ears, (lettered, respectively, k and p'), by 90 means of which ears and suitable bolts these casings are rigidly, but removably, attached to the front wall of the casing.

The upper casing k is arch-shaped and is closed at its front end by a furnace-door K'. 95 The lower casing P is similar in shape and forms an extension of the ash-pit and is closed at its front end by the ash-pit door P'.

The casing L is bolted on the top wall of the ash-pit casing P and tapers inwardly and 100 opens into the fire-box just above the grate. The door L' is mounted on the front wall of the main casing in such position as to close the forward end of the casing L.

The bottom of the feed-casing K is provided with a graded opening n, and connecting this hole with a similarly-sized hole o in the top wall of the casing l is a vertical tube m. In the top wall of the casing P, which also forms the bottom wall of the casing L, is 110 a hole o', which coincides with the hole o.

The casing L is secured, by means of suit-

able bolts and ears l' , to the top of casing P and the front side of the end wall C and by means of slotted ears l and suitable bolts to the front wall of the casing, as shown more particularly in Fig. 6.

The grate-frame G is provided with lateral under lugs g' , which work in opposite longitudinal grooves formed in cast bars G' , riveted to the opposite inner walls of the elliptical shell. These grooves are continued at p in the ash-pit casing, whereby the entire grate-frame may be slid forward and out of the furnace through the ash-pit door P' .

The rocking grate-bars g^2 may be of any suitable construction and may be operated by depending bars g^3 , a connecting-rod g^4 , and a lever b' , journaled on a pivot g^5 in front of the casing.

The fire-pot consists of the four cast sections F , which are supported on the bars G' , riveted to the interior of the shell. These sections are independently removable through the feed-door, and when in place they form a rectangular fire-pot. The faces of all the sections are vertically fluted or corrugated, and in addition the side sections and the front section have their top edges curved outward, so as to form air-spaces between these sections and the adjacent walls of the fire-box. A series of holes f' are formed in each of these sections to conduct the air out over the fire. Coincident with the inner end of the tubular casing L the front section F is provided with a hole f^2 to permit a clinker-bar to be passed into the fire-pot to break up and remove the clinkers.

To supply air to the air-space formed by the front section and thence into the side air-spaces, I provide two horizontal tubes v , which extend from openings v' in the front wall of the fire-box to coincident holes in the front plate of the main casing, these latter holes being covered by registers w .

It will be observed that in my invention I provide a strong and durable furnace which is adapted to burn hard or soft coal or wood and which shall be inexpensive to manufacture and easy of repair, as all the parts are accessible. It will be observed that I provide for a long fire travel, and thereby obtain a maximum heat from a minimum of fuel, and in order that the draft shall be facilitated and the greatest amount of radiation obtained when the damper j is closed I make the lower fire-flue h larger than the upper one.

A feature of importance lies in constructing the body of the furnace proper of a steel shell and bolting thereto the flanged end walls, whereby a very strong and inexpensive construction is obtained. The steel strap-bolts b are important in that they permit expansion and contraction of the shell without loosening the parts, whereas should long bolts be employed to connect the two heads or end walls the bolts would expand and contract

and loosen the joints between the end walls and the ends of the shell.

Another feature of importance lies in casting the feed-pouch and ash-pit extension upon the front cast wall of the furnace and in removably connecting it to the front wall of the main casing, whereby the parts are easily and quickly manufactured and assembled and are, furthermore, readily accessible for cleaning out and repairing. As will be observed, the holes o and o' and tube m permit the dust from the ash-pit to be drawn up into the fire-box when the ash-door is opened, thereby preventing the dust escaping into the furnace-room. The manner of fastening and the location of the clinker-bar, tube, or pouch l is also advantageous on account of convenience of fastening it in place together with the dust-flue m .

It will be observed, further, that by my construction I reduce the number of parts and joints to a minimum and also that I reduce the height of the furnace to a minimum without reducing the radiating-surface, whereby my furnace is well adapted for use in low basements, as it permits ample elevation to be given to the hot-air pipes.

A further feature of importance lies in the provision of air-spaces behind the fire-pot linings, whereby an ample supply of heated air may be supplied to the combustion-chamber, which will be especially desirable when burning soft coal. These air-spaces also prevent the cast sections of the fire-pot from becoming overheated.

Other minor features of construction and advantage will be observed by those skilled in the art.

It will be apparent to those skilled in the art that various mechanical embodiments of the invention are possible, and I therefore do not wish to be limited to the exact arrangement and construction shown.

What I claim, and desire to secure by Letters Patent, is—

1. In a heating-furnace, the combination of a shell-like fire-box including an ash-pit having an end wall bolted over each end thereof, the front wall being provided with a feed casing or tube and an integral casing forming an extension of the ash-pit, this latter casing being provided with grooves p in its opposite sides, longitudinal supporting-strips G' attached along the opposite sides of the fire-box and provided with grooves registering with said grooves p in the ash-pit extension, a grate-carrying frame provided with oppositely-extending lugs slidable in said grooves, fire-pot sections within the fire-box, the side sections resting on said strips G' and the front and back sections resting at their ends upon said strips and intermediate their ends upon the grate-frame, a casing inclosing the fire-box and having its front wall bolted to the feed-chute and ash-pit extension.

2. In a heating-furnace, the combination of a shell-like fire-box, a removable end wall bolted over each end thereof, the rear wall being provided with a smoke-outlet and the front wall being provided with two air-inlets v' , an integral feed-chute K and an integral ash-pit extension P, the top of the ash-pit extension and the bottom of the feed-chute being each provided with an opening, a casing L provided with a hole in its top bolted over the opening in the top of the ash-pit extension, a vertical tube m connecting the hole in the top of the casing L to the hole in the bottom of the feed-chute, a sectional fire-pot supported within the fire-box and having air-chambers between its sections and the shell-like wall of the fire-box, these air-chambers

being in communication with the said inlets v' , a casing whose front wall is bolted to the front ends of the casings K, L, and P and is provided with openings and doors opening into said casings, air-tubes connecting said inlets v' with the openings in the front wall of the furnace, which latter openings are controlled by registers, and a series of heating-flues between the fire-box and the casing.

In testimony whereof I hereunto affix my signature, in the presence of two witnesses, this 11th day of April, 1905.

CHARLES N. BRETT.
